UNITED STATES PATENT OFFICE.

JOHN NAGY, OF JESSUP, PENNSYLVANIA.

DRILL SUPPORT.

Application filed September 30, 1927. Serial No. 222,955.

This invention relates to improvements in drill support, and has more particular reference to a device especially serviceable for use in supporting and seating a drill to its work, such as when drilling "shot" holes in coal mines and the like.

The primary object of the invention is to provide a drill supporting and seating device which is extremely simple and durable in construction as well as efficient and reliable in operation.

Another object is to provide a supporting and seating device for rock drills and the like especially suitable for use in mining operations and capable of being readily set up for use.

Still another object is to provide a device of the above kind including a pair of extendable props or pillars adapted to be erected in tandem relation and having lateral means near corresponding ends for supporting the ends of a drill guiding platform, and weight-operated means for sliding the drill on the platform so as to feed the drill bit to its work, the platform supporting means and the feeding means being so constructed as to permit the device to be inverted for facilitating drilling either adjacent the roof or adjacent the floor of the mine as desired.

Other objects will appear as the nature of the invention is better understood, and the same consists in the novel form, combination and arrangement of parts hereinafter more fully described, shown in the accompanying drawings and claimed.

In the drawings, wherein like reference characters indicate corresponding parts throughout the several views,

Figure 1 is a side elevational view of a drill supporting and seating device constructed in accordance with the present invention, the device being erected for use in drilling holes adjacent the roof of a mine;

Figure 2 is a top plan view of the device shown in Figure 1;

Figure 3 is a view similar to Figure 1 with the drill supporting and feeding device inverted and in use for drilling a hole adjacent the floor of the mine;

Figure 4 is an enlarged fragmentary transverse section taken upon line 4-4 of Figure 3;

Figure 5 is an enlarged end elevational view looking toward the right of Figure 1, with parts omitted and parts broken away;

Figure 6 is a fragmentary longitudinal section of one of the supporting props;

Figure 7 is a perspective view of one of the lateral platform supporting arms or bolts together with the clamping bolt of its associated platform clamp; and

Figure 8 is an enlarged transverse section taken on line 8-8 of Figure 1.

Referring more in detail to the drawings, the present invention comprises a pair of similar supporting props or pillars 5 in the nature of extensible jacks adapted to be erected in tandem relation and in an upright position adjacent the face 6 of the mine as shown in Figures 1 and 3, the props having opposite pointed ends 7 and 8 for engagement with the floor and the roof of the mine in a well known manner whereby the props are firmly mounted and maintained in the desired upright position.

As shown, each prop or pillar embodies a tubular upper section 9, an intermediate section 10 whose upper end is adjustably telescoped into the upper section 9 and the lower end of which is hollow and internally threaded as at 11 (Figure 6), and a further end or lower section 12 having a threaded upper end portion 13 adapted to be adjustably threaded into the lower end portion of the intermediate section 10 and provided with lateral handles 14 for facilitating manual turning thereof. For securing the end section 9 and intermediate section 10 in relative longitudinally adjusted positions, the adjacent ends of these sections are provided with longitudinal series of transverse openings 15 and 16 adapted to be selectively registered for reception of a removable pin 17 whereby the sections are held in adjusted relations for obtaining a rough adjustment of the props or pillars to approximately the desired length.

When the props or pillars are thus adjusted, corresponding pointed ends of the same are engaged with the floor of the mine, whereupon the end sections 12 are turned for threading the same outwardly of the intermediate sections 10 and causing the opposite pointed ends of the props to engage the roof of the mine. This causes the pointed ends of the props to embed themselves into the floor and roof of the mine so that the props are effectively maintained in the upright tandem relation desired.

Adjustable vertically or longitudinally on the end sections 9 of the props are split

clamps 18 having lateral arms 19 adapted for supporting reception of the ends of a drill supporting platform 20. The outer or free ends of the arms 19 are provided with removable and reversible screw clamps 21 adapted for engagement with the outer side of the platform 20 for firmly clamping the latter upon the supporting arms 19 as clearly illustrated in the several views. By permitting the clamps 21 to be removed and reversed, the platform 20 may be clamped against opposite sides of the arms 19 so that the supporting props may be employed as shown in Figure 1 for supporting the drill adjacent the roof of the mine or so that the props may be reversed end for end to support the platform and drill adjacent the floor of the mine as shown in Figure 3.

The platform 20 is formed in its upper surface with a longitudinal guideway or groove 22 adapted to slidably receive the lower part of the casing of the drill 23 for effectively guiding the latter for sliding movement longitudinally of the platform 25 and toward the face 6 of the mine. The drill is preferably of the reciprocating or impact type having a cross handle 24 at one end for facilitating manual guiding and steadyng of the drill whose cutting bit is 30 generally indicated at 25. Obviously, by vertically adjusting the clamps 18, the drill may be supported at the desired distance from the roof of the mine or from the floor of the latter.

The platform 20 is bifurcated at its forward end to provide a pair of side arms 26, and mounted upon a transverse axis 27 between these arms is a guide pulley 28. Connected to opposite ends of the drill handle 40 24 are flexible members or cables 29 adapted to be extended forwardly and over the pulley 28 and having a weight 30 connected to the depending end thereof. It will thus be seen that as the drilling proceeds, the weight 45 30 will lower for automatically feeding the drill 23 and its bit 25 to the work or toward the face 6. The description just given applies particularly to the use of the device as illustrated in Figure 1, but when the device is employed as in Figure 3 to support the drill adjacent the floor of the mine, the free ends of the cables 29 are adapted to be connected to a single cable 31 having the weight 30 attached to the free end thereof,

the cable 31 being extended under and around a guide pulley 32 journaled upon the outer end of a lateral arm 33 which is carried by the clamp 18 of the forward prop so as to be disposed above the adjacent arm 19 when the props are inverted. The cable 60 31 is then extended from pulley 32 upwardly over a further guide pulley 33 supported upon a lateral arm of a split clamp 34 mounted upon the end sections 12 of the forward prop, as shown. In this way, the weight 30 is allowed sufficient drop for complete feeding of the drill to its work even though the drill is supported at a low elevation as shown in Figure 3.

From the foregoing description it is believed that the construction and operation as well as the advantages of the present invention will be readily understood and appreciated by those skilled in the art.

Minor changes may be made without departing from the spirit and scope of the invention as claimed.

What I claim as new is:

1. In combination, a pair of extensible props having lateral supporting arms adjacent corresponding ends, a drill supporting and guiding platform, means to secure the platform upon either of the corresponding sides of said arms, whereby the drill may be selectively supported adjacent the roof or adjacent the floor of a mine upon inverting the props, and weight operated means for moving the drill on the platform when the drill is supported in either position.

2. In combination, a pair of extensible props having lateral supporting arms adjacent corresponding ends, a drill supporting and guiding platform, means to secure the platform upon either of the corresponding sides of said arms, whereby the drill may be selectively supported adjacent the roof or adjacent the floor of a mine upon inverting the props, weight operated means for moving the drill on the platform when the drill is supported in either position, said weight operated means embodying guides at opposite ends of one of the props, and flexible members adapted for connection with the drill and for selective cooperation with different ones of the guides.

In testimony whereof I affix my signature.

JOHN NAGY.
